UNITED STATES PATENT OFFICE.

WILBURN H. HENDERSON, OF EL PASO, TEXAS.

INTERNAL-COMBUSTION ENGINE.

Application filed June 27, 1923. Serial No. 648,047.

This invention relates to internal combustion engines.

Among the objects of the invention, the following may be enumerated; complete scavenging; fuel economy; greater power and structural strength for weight; ports of great capacity; large seating surfaces of relatively movable parts; markedly increased accessibility for cleaning and grinding meeting surfaces; high compression; simple and cheap construction from the manufacturing standpoint; and symmetrical design.

With the above and other objects in view, the invention consists in the novel construction, combination and arrangement herein described, shown and claimed.

In the accompanying drawings:—

Fig. 1 is a vertical transverse section through the improved engine.

Fig. 2 is a fragmentary vertical longitudinal section thereof.

Fig. 3 is a vertical cross section through the multiple cylinder head showing a part of the cooling means.

Fig. 4 is a diagram showing the four cycles of movement of the cylinder head and the intake, compression, firing and exhaust positions thereof.

Fig. 5 is a fragmentary, broken away perspective view showing the preferred contour of the upper part of the cylinders with valve.

Fig. 6 is an outside face view of one of the engine parts.

The invention is shown as applied to the tandem multiple cylinder internal combustion engine to which the improved features admirably lend themselves. It is to be observed, however, that the principles of the invention are capable of use in engines of one or more cylinders.

Each of the cylinders 1 is secured to a crankcase 2 and contains a piston 3 coupled by a connecting rod 4 to the crank shaft 5 in accordance with engineering practice. Each cylinder has a surrounding water jacket 6.

In carrying out the invention the valve member 7 is of hollow cylindrical formation and rotates in relation to the cylinders 1. The upper part of each cylinder is enlarged to allow for the formation at the top thereof of a concave seat 8 fitting closely the periphery of the valve member 7 as shown in Fig. 1.

The enlarged upper part of the cylinder

is also formed with an intake passage 9 at one side, and an exhaust 10 at the opposite side. It will be noted that the passages 9 and 10 are quite large thereby allowing for free movement of the inflowing and exhaust gases. The valve member 7 is held securely in place by a substantially cylindrical housing cap 11 removably held by bolts 12 or their equivalent.

For each cylinder 1, the valve member 7 is formed with three (more or less) combustion chambers 13 each cup shaped and approximately hemispherical and said head is rotated by any suitable gearing at one sixth crank shaft speed; therefore, during each complete cycle of operation including intaking, compressing, firing and exhausting, one only of said combustion chambers 13 is moved into and out of registry with the respective cylinder 1.

The spaces 14 between the combustion chambers 13 provide for the circulating of the cooling agent (usually water) and are designed to leave a sufficient and uniform thickness of wall 15 to allow for efficient cooling of the walls of the combustion chambers.

To obtain high compression the upper end of each piston 3 is made concave at 16 to conform to the arc of the periphery of the valve member 7, as shown in Fig. 1. Any required distance and space may be left between the piston and cylinder head for final compression.

Complete scavenging of each combustion chamber is effected as follows. Surmounting the housing cap 11 is an air conduit 17 of light weight sheet material fastened to the cap 11. Through the conduit 17 a constant flow of cool air is forced by the action of one or more fans or air propellers 18 upon and driven by a rotary shaft 19 which may be geared to any rotating element of the engine.

An opening 20 is made in the housing 100 cap 11 above each cylinder 1, and an air deflecting flange or projection 21 is arranged in the conduit above each opening 20, leaving a Venturi passage which increases the velocity of the cooling air stream as it passes 105 each combustion chamber. Therefore, as each combustion chamber registers with the opening 20, as indicated in Fig. 1, and also in second, third and fourth positions of Fig. 4, said combustion chamber is completely 110

scavenged of all burned gases and cooled and can thereafter receive a full clean charge as it passes the inlet passage 9.

The cooling of the cylinder head is effected by a flow of water through the head and against the walls of all the combustion chambers. Any means may be used to cause circulation of the cooling water, as for example propelling vanes or blades 22 projecting within the hollow or tubular portions of the valve member (see Figs. 2 and 3) to force the water along its route to a cooling radiator (not shown). Ports 23 in the valve member 7 afford communication between the interior of the valve member 7 and the cylinder water jacket 6.

Interfitting non-leak annular stops or ribs 24 may be used on the meeting faces of the valve member 7 and the seating surfaces therefor as indicated in Fig. 2.

To obtain quick opening and closing of the intake and exhaust ports of the engine and the bore of each cylinder, said ports and passages may be of rectangular contour as shown best in Figs. 5 and 6. The shape of an intake port is shown in Fig. 6. Fig. 5 shows a corresponding shape for the upper end portion of the cylinder bore, the metal being milled out so as to present four straight sides or edges 25 opposite ones of which are parallel.

The cycle of operation of the engine is diagrammatically shown in Fig. 4. In position one, a compression chamber is fully registered with the cylinder bore and the piston is at the firing point. In the second position the piston is at the end of the firing stroke and the head is just cracking open the exhaust passage. In the third position the exhaust stroke is completed and the head is cracking open the intake passage. In the fourth position the piston has completed its suction stroke and the head has closed the intake passage. The full cycle is then repeated indefinitely. Three complete cycles of operation are had for each and every complete revolution of the valve member 7. Before each combustion chamber is returned to functioning position, shown in Fig. 1, it is effectively cooled by the action of water and cool air, and is completely scavenged by a blast of cool air.

The construction described and shown enables the valve member 7 to be ground to a seat in the same manner as a crank shaft bearing, the housing cap 11 being removable for that purpose. The engine is especially adapted for aircraft on account of its light weight for horsepower developed and economy in fuel consumption due to high compression. The combustion chamber is almost spherical in shape permitting ready combustion. A new charge will not be diluted by the hot residue of an old charge, thus admitting of higher compression as

well as fuel economy. This will materially increase the radius of cruising and climbing efficiency of the engine. The way of valving the gas, both intake and exhaust, renders the engine practically noiseless and gives a great range of speed on the engine shaft.

Carbon may be removed through the exhaust port without demounting a single part of the engine, either by burning or scraping. Lubrication of bearing surfaces of the engine may be obtained by the usual automotive methods.

I claim:

1. In an internal combustion engine, a cylinder, a piston, a valve member rotatable in relation to the cylinder and having a combustion chamber which moves into and out of registry with the bore of the cylinder, means internal of said valve member for constantly cooling the walls of said combustion chamber, and means for inducing a flow of cool air over the outer walls of said valve member.

2. In an internal combustion engine, a cylinder, a piston, a valve member rotatable in relation to the cylinder and having a combustion chamber which moves into and out of registry with the bore of the cylinder, means internal of said valve member for constantly circulating a cooling agent about the walls of said combustion chamber, and means for inducing a flow of cool air over the outer walls of said valve member.

3. In an internal combustion engine, the combination of a cylinder, a piston, a valve member rotatable in relation to the cylinder and having a combustion chamber which moves into and out of registry with the bore of the cylinder, and means for scavenging said combustion chamber while out of registry with said bore, said scavenging means comprising a conduit having a port registering with said combustion chamber and a fan in said conduit to expel the waste products in said combustion chamber.

4. In an internal combustion engine, the combination of a cylinder having an enlarged head portion, said head portion having intake and exhaust ports, and a semi-circular bore, a detachable housing having a semi-circular bore adapted to be secured to said head portion to form a circular bore, said housing having an opening, a valve member rotatable in said circular bore having a plurality of combustion chambers, a piston in said cylinder, and means for scavenging the waste products in the combustion chamber when said chambers are in registry with the opening in said detachable housing, and for causing a continuous flow of cooling air over the outer wall of said valve member.

5. In an internal combustion engine, the combination of a cylinder having an en-

larged head portion, said head portion having intake and exhaust ports, and a semi-circular bore, a detachable housing having a semi-circular bore adapted to be secured to said head portion to form a circular bore, said housing having an opening, a valve member rotatable in said circular bore having a plurality of combustion chambers, a piston in said cylinder, and means including 10 a conduit having an opening in the detachable housing and an air propeller in said conduit to expel the waste products of combustion when said combustion chambers are in registry with the opening in said housing.

15 6. In an internal combustion engine, the combination of a cylinder having a water jacket, a piston in said cylinder, a valve member rotatable in relation to the cylinder and having a plurality of combustion chambers which move into and out of registry 20 with the bore of said cylinder, said valve member having passageways surrounding said combustion chambers, and means for

circulating a cooling agent through said passageways, and means for inducing a constant flow of cooling medium to scavenge said combustion chambers. 25

7. In an internal combustion engine, the combination of a cylinder having an enlarged head portion, said head portion having intake and exhaust ports, and a semi-circular bore, a detachable housing having a semi-circular bore adapted to be secured to said head portion to form a circular bore, said housing having an opening, a valve member rotatable in said circular bore having a plurality of combustion chambers, a piston in said cylinder, and means including 30 a flow of cooling air for scavenging the waste products in the combustion chamber when 35 said chambers are in registry with the opening in said detachable housing, and said other combustion chambers are out of registry with the bore of said cylinder. 40

In testimony whereof I affix my signature.
WILBURN H. HENDERSON.
